UNITED STATES PATENT OFFICE.

JOHN H. NEWELL, OF SCOTTVILLE, ILLINOIS, ASSIGNOR TO HIMSELF AND
ALFRED M. GREER, OF SAME PLACE.

WINDMILL-REGULATOR.

SPECIFICATION forming part of Letters Patent No. 258,462, dated May 23, 1882.

Application filed April 7, 1882. (No model.)

To all whom it may concern:

Be it known that I, JOHN H. NEWELL, of Scottville, in the county of Macoupin and State of Illinois, have invented a new and Improved 5 Windmill-Regulator, of which the following is a full, clear, and exact description.

This invention relates to windmill-pumping apparatus for supplying water for stock; and it consists of a float in the water-tank, weights, 10 and catch and trip dogs for automatically setting the wind-wheel to work when the water-supply runs low in the tank, and stopping it when the tank is full. When the water rises to the high level in the tank the float trips a 15 weight that pulls the wind-wheel around into the plane of the tail-vane and stops the pump. The weight is at the same time caught by a catch-dog and held until by the fall of the water to the low level the float trips another 20 weight of greater capacity than the first, that lifts the said first weight to release the wind-wheel and allow it to work, and at the same time sets said first-mentioned weight by a catch-dog, to be held so that the wheel will 25 continue to run until the water rises again and the float again trips the weight that shifts the wind-wheel, as in the first instance, all as hereinafter more fully described.

Reference is to be had to the accompanying 30 drawings, forming part of this specification, in which similar letters of reference indicate corresponding parts in both the figures.

Figure 1 is a sectional elevation of the water-tank and side elevation of the said apparatus and a portion of the wind-wheel tower, and Fig. 2 is a perspective view of the apparatus.

A represents the tower, whereon the wind-wheel is supposed to be mounted for working 40 the rod B of the pump, the said wheel being of the kind which is stopped by shifting it around into the plane of the tail vane, in which position the wind has no rotative effect on the wheel, and which said wheel is set in motion 45 by being released from that position and allowed to assume the working position.

C represents a cord or wire that is connected to the wind-wheel, as in the common arrangement, for so pulling it out of the wind when 50 said cord is pulled down by the weight D, and

releasing and allowing it to work when said weight is raised. This weight D is connected to one arm of a lever, E, for setting and holding said weight in the different positions and tripping it when it is to be shifted. In Fig. 1 55 the lever is set by the catch-dog M for holding the weight up to allow the wind-wheel to run and work the pump, the water being low in the tank H.

F is a weight larger than D, and resting on 60 the float G in the tank when not suspended on lever E. Weight F has a loop or bail, I, hung over the arm of lever E, next to the catch-dogs, and of sufficient length to allow the weight to rise under the lever, when set by 65 catch M, as high as the weight will be floated by high water without interfering with said lever. The bail works in guide-loops J in the sides of the lever. When the water rises to about the high-water level arm N on the float 70 G lifts the long arm of catch M and trips lever E, so that weight D falls and pulls down cord C to stop the wind-wheel, as above stated. At the same time the weight D throws up the other end of lever E above catch L, by which 75 it is caught and held, the weight D being down and the wind-wheel being inoperative. The bail I of weight F is at this time sufficiently high to allow the lever E to swing above catch L. The water now falls, float G descending, and leaving weight F suspended on lever E; when low-water mark is reached, trips arm O of float 80 G, pulls down the long arm of catch L, tripping lever E, and letting weight F fall; said weight being heavier than D, raises weight D 85 to allow the wind-wheel to work again; and it also sets lever E under latch M, to be held in that position, so that the wheel will continue to work the pump until the tank is full again.

The catch-dogs are mounted on a standard, 90 K, arranged in the plane of the sweep of lever E, and the said catch-dogs have springs P, that hold them in the positions for keeping the lever E, but which are overborne by the trip-arms N O for tripping the lever.

Having thus fully described my invention, I claim as new and desire to secure by Letters Patent—

1. The combination, with the pull-cord C of a windmill, and weight D suspended thereon,

of setting and tripping lever E, float G, weight F, catch-dogs L M, and tripping-arms N O, substantially as specified.

2. The combination of weight F, yoke L, and float G with the tripping-lever E, substantially as specified.

3. The catch-dogs L M, combined with the lever E, weight F, float G, and the trippers N O, substantially as specified.

4. The catch and trip dogs L M, arranged on the vertical standard K, in combination with the vertically-swinging shifting-lever E and the float G, said float having trippers N O, substantially as specified.

JOHN H. NEWELL.
